LIQUID FUEL DISTRIBUTING SYSTEMS FOR COMBUSTION ENGINES

Robert J. Thorpe, Shawnee, and Donald F. Winters, Overland Park, Kans., assignors to Westinghouse Electric Corporation, East Pittsburgh, Pa., a corporation of Pennsylvania

Application November 20, 1957, Serial No. 697,691

6 Claims. (Cl. 158—36)

This invention relates to a liquid distributing system, more particularly to a system for distributing liquid from a common supply to a plurality of dispensing nozzles at uniform pressure and has for an object to provide an improved and highly reliable system of the above type.

Although the invention provides a liquid distributing system which is susceptible of wide and diversified application, the system is primarily intended for distributing liquid fuel to an internal combustion engine, for example an aviation gas turbine engine, and is especially advantageous for fuel distribution in turbojet engines having a wide flight speed range or spectrum. Turbojet engines of this type require fuel distribution systems which uniformly distribute fuel to the dispensing nozzles throughout a wide flow range, on the order of 40 to 1 and within a pressure drop range extending from a minimum of about 50 lbs./sq. in. to a maximum of about 200 lbs./sq. in.

Accordingly, it is a further object of the invention to provide a liquid fuel distributing system for uniformly distributing fuel to a plurality of nozzles throughout a wide flow range and within pressure drop limits suitable for a wide flight spectrum aviation engine.

In accordance with the invention, there is provided a system for distributing fuel to a plurality of dispensing or injecting nozzles including a manifold communicating with a supply pipe and a plurality of positive displacement pumps having their inlets and outlets connected to each other in a series hydraulic loop-servo circuit which is connected at its ends to the supply pipe. In the servo circuit there is interposed a valve, responsive to differential pressure, for controlling the total or cumulative fuel pressure rise across all of the pumps at a desired value. Each of the pumps is coupled to an associated set of positive displacement fuel actuated motors having their inlets connected to the manifold and their outlets connected individually to the injecting nozzles.

Thus, as fuel at suitable pressure and in metered quantity is delivered to the manifold by the supply pipe, it flows into the inlets of the fuel actuated motors to drive the same and is thence delivered to the nozzles at a reduced pressure. Since the motors drive the pumps, the total pressure drop occurring across each set of motors is substantially equal to the pressure rise across the associated pump. By suitable adjustment of the valve, the total pressure rise in the servo-loop circuit, and accordingly the pressure drop at the nozzles, may be closely controlled at any desired value.

The valve may be of the fixed adjustment type when the distribution system is employed with a suitable fuel metering control mechanism. However, a manually adjustable valve mechanism, responsive to suitable engine operating conditions such as rotational speed of the shaft, may be employed for selectively controlling the pressure rise in the servo circuit and accordingly the distribution pressure at the fuel nozzles.

The foregoing and other objects are effected by the invention as will be apparent from the following description

2

and claims taken in connection with the accompanying drawings, forming a part of this application, in which:

Fig. 1 is a diagrammatic transverse sectional view of an aviation turbojet engine having an embodiment of the invention incorporated therein;

Fig. 2 is an enlarged axial sectional view of one of the pump and motor units shown in Fig. 1;

Fig. 3 is a transverse sectional view taken on line III—III of Fig. 2, looking in the direction of the arrows;

Fig. 4 is a view similar to Fig. 1, but illustrating a second embodiment of the invention; and

Fig. 5 is a chart illustrating the performance curve attained with the invention and representative curves attained with prior art devices.

Referring to the drawings in detail, in Fig. 1 there is shown a typical aviation turbojet engine 10 having a fuel distributing system 11 formed in accordance with the invention.

Since the turbojet engine 10 does not form a part of the invention, it has been shown diagrammatically in transverse section taken through the fuel combustion chamber 12 and looking in upstream direction. As well known in the art, the turbojet engine 10 has an outer tubular casing 13 encompassing the usual air compressor and gas turbine portions (not shown), coupled for joint operation by a centrally disposed rotatable engine shaft 14, and driven by hot motive combustion gases formed in the combustion chamber 12 and directed through the gas turbine before ejection to the atmosphere in a propulsive jet.

The combustion chamber 12 is of annular shape and is defined by tubular inner and outer wall structure 16 and 17 disposed in spaced concentric relation with each other about the engine shaft 14.

Fuel for combustion is admitted to the combustion chamber 12 by an annular row of dispensing or injecting nozzles 18, which may be of any suitable variable area type or vaporizing type, as desired. As well known in the art, the nozzles 18 are uniformly spaced from each other to admit fuel in highly atomized or otherwise finely divided condition in a uniform pattern to the combustion chamber, thereby to promote a good fuel/air mixture and to obviate formation of localized "hot spots."

The fuel system 11 has a supply pipe 19, provided with fuel from any suitable source (not shown), communicating with an annular manifold 20 which is mounted concentrically with the engine 10. The fuel supply pipe 19 has interposed therein a main fuel pump 21 and a fuel metering control mechanism 22 of any suitable type for regulating the flow of fuel from the pump 21 into the manifold 20, as well known in the art.

In accordance with the invention, the fuel manifold 20 has attached thereto at uniformly spaced intervals a plurality of motor-pump units, generally designated 23, for regulating the delivery of fuel from the manifold 20 to the nozzles 18. Since the motor-pump units 23 may be identical, only one will be defined, it being understood that the others are arranged and formed in a similar manner. As best shown in Figs. 2 and 3, the motor-pump unit 23 has a pump element 24 and a plurality of motor elements 25 similar to the pump element 24 but of slightly smaller capacity. The motor elements 25 and the pump element 24, as illustrated, are of the positive displacement rotary vane type.

The pump element 24 includes a rotor member 26 mounted on a shaft 27 which is rotatably mounted in a generally cylindrical housing 28 provided with a fuel inlet 29 and a fuel outlet 30. The rotor 26 has a plurality of vanes 31 slidable radially to maintain abutment with the inner surface of the housing 28 during rotation of the shaft, thereby to translate fuel from the pump inlet 29 to the pump outlet 30.

The motor elements 25 are similar to the pump element 24 and are individually provided with vaneed rotors 32 mounted to the shaft 27 and having fluid inlets and outlets 33 and 34, respectively. The motor outlets 34 are (as shown in Fig. 1) connected to the associated fuel injecting nozzles 18 by individual conduits 35 while the motor inlets 33 (as shown in Fig. 2) communicate with a manifold 36 formed in the housing 28 and having a common inlet 37 formed therein which is connected to the annular manifold 20. Thus, fuel from the annular manifold 20 is delivered to the manifold 36 through the common inlet 37 and thence divided for flow through each of the inlets 33 to provide motivating fuel to each of the motor elements 25.

Thus, it will be seen that the motor elements 25 and the pump element 24 rotate jointly and at the same speed, the motor elements 25 receiving motivating fuel from the common inlet 37 and jointly driving the pump element 24, while the pump element 24 is fed fuel through the pump inlet 29 and delivers it through an outlet 38 communicating with the outlet 30.

The pump elements 24 are connected to each other in a loop-servo circuit by a plurality of conduits 39 connected at their upstream ends to the pump outlets 30 and at their downstream ends to the pump inlets 29, thereby forming a series flow circuit from one pump to the next. The first pump element 24 in the servo circuit (disposed at nine o'clock in Fig. 1) has its inlet 29 connected to the supply pipe 19 by a conduit 40, thereby to provide the servo-loop circuit with fuel at supply pipe values, while the outlet of the last pump element 24 in the servo circuit (disposed at seven o'clock in Fig. 1) has its outlet 39 connected to a differential pressure valve 42 by a conduit 43.

The differential valve 42 has a housing within which is mounted a slidable valve member 44 having a pair of spaced lands 45 and 46 connected to each other and biased upwardly by a spring 47. The upper end of the valve 42 is connected to the supply pipe 19 by a conduit 48, while the lower end of the housing is connected to one of the fuel nozzle conduits 35 by a conduit 49, thereby to provide supply fuel pressure upon the slidable valve 44 in opening direction and fuel nozzle pressure in closing direction. The valve 42 is further provided with an inlet 50 and an outlet port 51, the latter being regulated by the lower land 46. The outlet port 51 is connected to the supply pipe 19 by a conduit 52. Thus, it will be seen that the servo-loop circuit is provided with fuel from the supply pipe 19 flowing through the conduit 40 and the pump elements 24 by way of the conduits 39 and thence through conduit 43, the differential pressure valve 42 and conduit 52 back to the supply pipe 19.

The fuel system 11 operates in the following manner. As fuel, pumped by the main pump 21, is delivered to the manifold 20 at regulated flow rate and pressure values by the fuel control 22, the rotors 32 of the motor elements 25 are driven and the fuel ejected therefrom through the outlets 34 is delivered to each of the associated nozzles 18 at a reduced pressure value. Since the motor rotors 32 of each motor-pump unit 23 are interlocked, the fuel delivered to each of the fuel nozzles 18 is uniform in volume, insofar as each of the motor-pump units 23 is concerned. However, since the pump elements 24 are driven by the motor elements 25, and since each of the pump elements 24 is connected to all of the other pump elements in the servo-loop circuit by conduits 39, the pumped fuel must pass through each of the pump elements 24. In this manner, the pumped volume is equal for all pump elements 24, hence the R. P. M.'s of all pumps are equal, thereby insuring uniform flow through the motor elements 25 and uniform flow through all of the fuel injecting nozzles 18.

The motor elements 25 perform work in driving the associated pump element 24. Hence, a pressure drop

is effected across each of the motor elements 25, and the sum of the work accomplished by each of the motor-pump units 23 is converted to the pressure rise across the associated pump element 24. Accordingly, the sum of the pressure rises across each of the pump elements 24 is transmitted to the valve 42 by the conduit 43. The valve 42 serves to regulate the total pressure rise in the loop-servo circuit at a preselected value to insure that the pressure drop across the motor elements is maintained within certain preselected limits in the following manner.

As fuel from the supply line 19 is delivered to the fuel manifold 20 by the fuel metering control 22 at a selected rate of flow, the motor rotors 32 of each of the motor-pump units 23 are rotated and, in turn, drive the associated pump rotors 24. The resulting pressure drop across the motor elements 25 is transmitted to the valve 42 by the conduit 49, thereby modifying the position of the valve land 46 as required to regulate the area of the valve port 51. The pressure rise across the pump elements 24 is thus regulated by the valve and concomitantly controls the pressure drop across the motor elements 25 in a manner to permit uniform distribution of fuel to each of the injector nozzles 18.

During operation of the engine 10, the fuel rate to the injector nozzles 18 may be increased or decreased within prescribed limits by the fuel metering control 22, for reasons well known in the art. Should the fuel metering control 22 be adjusted for an increased flow rate so that the fuel from the supply pipe 19 is delivered to the manifold 20 at a higher flow rate, the motor elements 32 rotate at a faster rate, thereby to deliver fuel to the fuel nozzles 18 at a higher rate as indicated by the fuel metering control 22. Such increase in flow rate of the motor elements will momentarily result in an increase in pressure drop across the motor elements with a momentary increase in the pressure rise across the pump elements. The momentary increase in pressure drop across the motor elements, however, is transmitted to the differential valve 42 by the conduit 48 as a pressure increase, moving the valve land 46 downwardly to increase the area of the outlet port 51 until a stabilized position is obtained wherein the desired pressure rise in the servo-loop circuit is attained.

Should the fuel metering control 22 be adjusted for a reduced flow rate, the rate at which fuel is delivered through the manifold 20 to the motor-pump elements 23 is reduced and hence is effective to reduce the rotational speed of the motor elements 25 and create a smaller pressure drop across the motor elements with reduced rate of flow to the nozzles 18. The momentary decrease in pressure drop across the motor elements 25 is effective to provide a decreasing pressure rise across the pump elements 24. However, the decrease in pressure drop across the motor elements is effective as a decrease in pressure at valve 42, permitting the valve land 46 to move in upward direction, thereby decreasing the effective area of the port 51 of the valve and restoring the pressure rise value.

Referring to the chart in Fig. 5, wherein the abscissa denotes the pressure drop in pounds per square inch of the distribution system (effective across the motor elements 25) and the ordinate denotes the ratio of fuel flow rates metered by the metering control 22 within its range, the curve A graphically illustrates the operating characteristics of the above described system. In aviation jet propulsion engines having a wide flight speed spectrum, for adequate performance, the maximum and minimum practical pressure drops in the distribution system is about 200 pounds per square inch and 50 pounds per square inch, respectively, and the desired fuel flow rate ranges from a minimum to maximum of about 1 to 40. It will be readily seen that the straight line portion of curve A lies within the above mentioned limits, thus indicating that the invention is highly suitable for aviation engines

having a wide flight speed spectrum. More particularly, it will be noted that at minimum fuel flow rate of 1 the pressure drop is about 80 pounds per square inch, while at the maximum flow rate of 40 the pressure drop is 150 pounds per square inch.

For comparison purposes, curve B, depicting performance characteristics of a conventional fixed orifice fuel distributor, and curve C, depicting performance characteristics of a known fuel distributor having variable area orifices, are also shown on the chart.

It will readily be apparent, by referring to curve B, that the fuel distributor of the fixed orifice type has limited application value, since the pressure drop across the orifice is too low for proper distribution at low flow rate values and quickly rises to excessive pressure values at a practical maximum flow rate of about 10.

The variable orifice area distributor is considerably better than the fixed orifice distributor and may be employed in wide flight spectrum engines, since it can deliver fuel at rates ranging from 10 to 40 within the pressure drop limits of 50 p. s. i. to 200 p. s. i. However, at flow rates of less than 10 the fuel pressure drop is lower than desired. In addition, the variable area distributor requires extreme manufacturing precision in order to uniformly distribute fuel to a plurality of nozzles.

In Fig. 4 there is shown a fuel distributing system of somewhat modified form. Since most of the structure has already been described in connection with the first embodiment, that structure is designated by the same reference numerals heretofore employed.

In this embodiment, a suitable bypass conduit 55 is provided communicating with the inlet and the outlet of the main fuel pump 21, whereby to permit recirculation of excess fuel pumped by the fuel pump 21. The rate at which the excess fuel recirculates therethrough is regulated by a differential pressure valve 56 having a port 57 controlled by a slidable piston valve member 58. The piston valve is subjected to opposing fuel pressures of the supply pipe 19 transmitted thereto by conduit 48 and distribution pressure of the injector nozzles 18 transmitted thereto by conduit 49.

A fuel control valve 60 is interposed between the conduits 43 and 52 for regulating the cumulative fuel pressure rise in the servo-loop circuit of the pump elements 24, and accordingly the pressure drop across the motor elements 25. The fuel control valve 60 has a housing 61 within which is rotatably mounted a hollow cylindrical member 62 driven in any suitable manner (not shown) by the engine shaft 14 and provided with a pair of axially spaced ports 63 and 64 communicating with the conduits 52 and 43, respectively. Within the rotatable member 62, there is slidably disposed a piston valve member 65 having a land 66 arranged to vary the area of the port 64. The upper end of the valve member 65 has a circular platform 67 upon which is received a helical speeder spring 68 for biasing the valve member 65 downwardly, i. e. in the direction to open the port 64. The bias of the speeder spring 68 is adjustable by a pivoted throttle lever 69 having a cam portion 70 for adjusting a plunger 71 which abuts the speeder spring 68. Thus as the throttle lever is rotated in clockwise direction, from the off position shown, the spring bias is increased. A plurality of suitable flyweight members 72, pivoted to the rotatable cylinder 62, are employed for opposing the downward bias of the speeder spring 68 on the valve member 65.

In operation, the throttle lever 69 is manually moved in clockwise direction to a selected engine speed setting, thereby biasing the valve member 65 downwardly in a direction to open the port 64. As the rotatable cylinder 62 is rotated by the engine shaft 18 the centrifugal force of the flyweights 72 is effective to oppose the bias of the spring and stabilize the valve 65. Hence fuel flows through the servo-loop circuit including the pump elements 24, conduit 43, valve ports 64 and 63, and conduit 52 to the supply pipe 19 at a suitable controlled

cumulative pressure rise value which is equal to the sum of the individual pressure rise values across each of the pump elements 24. Accordingly, the individual pressure drop values across each of the motor elements are controlled, in the manner described in connection with the first embodiment, to provide fuel at equal flow rate to the fuel injecting nozzles.

The fuel flow distribution rate may be increased by moving the throttle lever 69 in clockwise direction, thereby to increase the bias of the speeder spring 68 on the valve member 65. As the bias of the speeder spring is increased, the valve port 64 is opened to a greater degree by the valve member 65 and the position of the valve member is stabilized by the opposing centrifugal force of the flyweights acting against the speeder spring. Thus, the pressure rise in the servo-loop circuit is correspondingly decreased, with attendant reduction in the pressure drop across the motor elements 25. The thus reduced pressure drop across the motor elements 25 is transmitted to the valve 56 through the conduit 49 as a pressure increase, moving the piston valve 58 upwardly to reduce the effective area of the port 57 and increasing the fuel flow through the conduit 19 to the manifold 20.

Conversely, the fuel flow distribution rate may be decreased by moving the throttle lever 69 in counterclockwise direction, thereby decreasing the bias of the speeder spring 68. The pressure rise in the servo-loop circuit is correspondingly increased with attendant increase in pressure drop across the motor units 25, thereby causing the effective area of the valve port 57 to be increased, increasing the flow rate through the recirculation conduit 55 and decreasing the fuel flow rate through conduit 19 to the manifold 20.

It will be noted that in the embodiment shown in Fig. 1, the fuel metering control 22 is of conventional type and that all of the fuel delivered to the injector nozzles 18 passes through the control 22. However, in the embodiment shown in Fig. 4 the fuel control valve 60 is effective to regulate the fuel flow rate through conduit 19, although only the fuel flow through the servo-loop circuit traverses through the valve.

While the invention has been shown in several forms, it will be obvious to those skilled in the art that it is not so limited, but is susceptible of various other changes and modifications without departing from the spirit thereof.

What is claimed is:

1. A liquid distributing system comprising a liquid manifold, a liquid supply pipe communicating with said manifold, a plurality of positive displacement liquid pumps, a plurality of sets of positive displacement liquid actuated motors, each of said sets of motors being mechanically coupled to and driving an associated one of said pumps, each of said sets of motors having their inlets connected to said manifold, conduit structure connecting the inlets and outlets of said pumps in a series hydraulic circuit, valve structure disposed in said conduit structure for controlling the pressure rise across said pumps, the pressure rise across said pumps being effective to maintain a regulated pressure drop across said motors, and a plurality of liquid dispensing nozzles, each of said nozzles being connected to the outlet of an associated motor.

2. A liquid distributing system comprising a liquid manifold, a liquid supply pipe communicating with said manifold, a plurality of positive displacement liquid pumps, a plurality of sets of positive displacement liquid actuated motors, each of said sets of motors being mechanically coupled to and driving an associated one of said pumps, each of said sets of motors having its inlets connected to said manifold, conduit structure connecting the inlets and outlets of said pumps in a series hydraulic circuit, both ends of said conduit structure being in liquid communication with said liquid supply pipe to form a closed loop, a valve disposed in said con-

duit structure for regulating the pressure rise across said pumps, said valve being responsive to the differential pressure between the liquid in the outlet of one of said motors and the liquid in said supply pipe, and a plurality of liquid dispensing nozzles, each of said nozzles being connected to the outlet of an associated motor.

3. A liquid distributing system comprising a liquid manifold, a liquid supply pipe communicating with said manifold, a main pump in said supply pipe for delivering pressurized liquid to said manifold, a plurality of positive displacement pumps, a plurality of sets of positive displacement liquid actuated motors, each of said sets of motors being mechanically coupled to and driving an associated one of said positive displacement pumps, each of said sets of motors having its inlets connected to said manifold, conduit structure connecting the inlets and outlets of said positive displacement pumps in a series hydraulic circuit, a valve disposed in said conduit structure for controlling the pressure rise across said positive displacement pumps, means for automatically regulating said valve, means including a differential pressure relief valve for permitting recirculation of excess liquid about said main pump, said differential pressure relief valve being responsive to liquid pressure at the outlet of one of said motors, and a plurality of liquid dispensing nozzles, each of said nozzles being connected to the outlet of an associated motor.

4. A fuel distributing system for fuel combustion apparatus including a tubular wall structure and a plurality of nozzles for injecting fuel thereinto, comprising a fuel manifold, a fuel supply pipe communicating with said manifold, a plurality of positive displacement pumps, a plurality of sets of positive displacement fuel actuated motors mechanically connected to said pumps, each of said sets of motors having its inlets connected to said manifold and its outlets connected to said nozzles, conduit structure connecting the inlets and outlets of said positive displacement pumps in a loop-servo circuit, a valve disposed in said conduit structure for controlling the cumulative fuel pressure rise across all of said positive displacement pumps, the pressure rise across said positive displacement pumps being effective to maintain a controlled pressure drop across said motors, and means for automatically regulating said valve.

5. A fuel distributing system for an internal combustion engine having a fuel combustion chamber for providing hot motive gases of combustion, a plurality of fuel injection nozzles for delivering fuel to said chamber and a rotary shaft driven by said motive gases; comprising a fuel manifold, a fuel supply pipe communicating with said manifold, a main fuel pump in said supply pipe for

delivering pressurized fuel to said manifold, a plurality of secondary pumps, a plurality of positive displacement fuel actuated motors mechanically coupled to said pumps, each of said motors having its inlet connected to said manifold and its outlet connected to an associated one of said nozzles, conduit structure progressively connecting the inlets and outlets of said secondary pumps in a loop-servo circuit, said conduit structure connecting the inlet of the first one of said secondary pumps to said supply pipe and the outlet of the last one of said secondary pumps to said supply pipe, a valve disposed in said conduit structure between the outlet of said last secondary pump and said supply pipe for controlling the cumulative fuel pressure rise across all of said secondary pumps, said secondary pumps being substantially identical and the pressure rise across said secondary pumps being effective to maintain a controlled pressure drop across each of said motors, and condition responsive means for automatically regulating said valve in response to a variable condition in said engine.

6. A liquid fuel distributing system for an internal combustion engine having a rotary shaft, a fuel combustion chamber for providing hot motive gases of combustion for driving said shaft, and a plurality of fuel injection nozzles for delivering fuel to said chamber; comprising a fuel manifold, a fuel supply pipe communicating with said manifold, a main fuel pump in said supply pipe for delivering pressurized fuel to said manifold, a plurality of secondary positive displacement pumps, a plurality of positive displacement fuel actuated motors mechanically coupled to said pumps, each of said motors having its inlet connected to said manifold and its outlet connected to one of said nozzles, conduit structure serially connecting the inlets and outlets of said secondary pumps in a loop-servo circuit, said conduit structure connecting the inlet of the first one of said secondary pumps and the outlet of the last one of said secondary pumps to said supply pipe; and a valve interposed in said conduit structure for regulating the fuel pressure rise in said loop-servo circuit, said valve having a port communicating with said conduit structure, a movable valve member for regulating the effective area of said port, and means responsive to the speed of said rotary shaft for controlling the movement of said valve member.
